UNITED STATES PATENT OFFICE.

ADELMER M. BATES, OF CHICAGO, ILLINOIS, ASSIGNOR TO BATES VALVE BAG COMPANY, OF CHICAGO, ILLINOIS, A CORPORATION OF WEST VIRGINIA.

BAG-FORMING-TUBE PACKAGE.

Original application filed October 3, 1919, Serial No. 328,311. Divided and this application filed April 12, 1920. Serial No. 373,102.

To all whom it may concern:

Be it known that I, ADELMER M. BATES, a citizen of the United States, residing at Chicago, in the county of Cook and State 5 of Illinois, have invented a certain new and useful Improvement in a Bag-Forming-Tube Package, of which the following is a specification, the subject matter of which is divided out of copending application Ser. 10 No. 328,311.

My invention relates to a bag forming tube package which can be made up and stored until needed, when it may be placed in position in a bag filling and forming machine 15 in such wise that as the tube is filled and formed into bags the stored tube will be released from the package only as it is used. Another object is to provide an arrangement whereby a relatively great length of 20 bag tube may be compressed, carried and stored on a relatively short spindle or spool, whereby it may be put in place in a relatively small filling machine and whereby the material to fill the separate successive 25 bags may be introduced through the stored bag tube. Other objects will appear from time to time in the specification.

The subject matter of this present invention is based on material divided out of my 30 pending application Ser. No. 328,311, filed October 3, 1919, and I have illustrated this invention in exactly the same manner as the process now claimed in the other application is illustrated, for the purpose of correlating the two inventions and adding to the 35 ease of understanding them. My invention is diagrammatically illustrated in the accompanying drawings wherein:

Figure 1 is a diagrammatic illustration 40 of one process of making the tubes;

Figure 2 diagrammatically illustrates another process of making, filling and storing the tubes in connection with a single apparatus;

Figure 3 illustrates a stored tube in proper condition for use in a bag filling, closing and severing machine;

Fig. 4 is a view of the bottom of the structure shown in Fig. 3.

Like parts are indicated by like letters 50 in all the figures.

A is a roll of bag making fabric, the two edges of which are gathered together as at B and sewed to form a tube.

The finished tube C may be run on to a 55 reel D, whence, as desired, it may be removed therefrom and placed on a storing tube very much smaller in cross section than the diameter of the finished tube and provided at its lower end with a holding device, whereby a great length of tube may be assembled and retained on a short holding and filling tube.

E is a bag tube forming tube. The cloth of the roll is brought to this tube with its 60 edges together and here they are united, as for example by a sewing machine F. Then the tube is reversed to form the finished tube J with a longitudinal seam inside. This tube J in the process of its formation is fed 65 down onto the storage and filling tube, which is removably attached in position. When a suitable length of bag tube has thus been stored it is severed from the roll, or the entire roll may be made into a continuous 70 bag tube. The tube as it is resting on the holder is longitudinally collapsed until it takes the form J', and when the entire tube has been put on the holder the funnel J' is preferably attached to one end thereof. 75 The other end is provided with an enlargement J'', which may be of any form, as for example oblong, so as to distend and flatten the tube as shown in dotted lines in Figure 80 3. J' is a tension device or girdle which 85 rests on the enlargement J'' and under which the end J' of the bag tube passes this girdle may or may not be flexible or elastic as shown.

The result is a finished spool with an enlargement at each end and a length of 90 finished bag making tube threaded and longitudinally collapsed on the body of the spool between the two enlargements. If, as in the preferred form, the body of the spool 95 is a tube, then one enlargement assumes the form of a funnel preferably adapted to hold a quantity of material sufficient to fill one of the bags proposed to be formed from the tube, and the other enlargement takes 100 the form of a spreading device which when the bag tube is fed off distends the bag and brings its two sides somewhat closely together so as to facilitate the sewing or closing operation.

These spools or tubes consist therefore of two enlarged ends over one of which the bag tube may pass with difficulty and a 105

long body portion which is very much smaller in cross section than the distended bag tube, so that the latter can be compressed or puckered or collapsed thereon between the two end enlargements. It would be quite possible, of course, to store the tubes on spools with rod bodies, from which the bag tubes could be subsequently transferred to the filling tubes of the filling machine.

10 The use and operation of my invention is as follows:

After the tube which is subsequently to be formed into bags has been made, it becomes necessary to store that tube in such form that it can be transported from the place where it is made to the place where the bags are to be made and filled, and preferably the device upon which the tube is transported and stored is the filling tube through which the material will pass to fill the bags and as in actual operation it would be impractical and uneconomical to make a short length of tube, I am concerned with the case where a great length of tube is made, as for example a tube equal in length to the entire length of the roll of fabric. Such tube, since the material must be fed into it from one end to the other, must be compressed within a very short length and this is done by threading and collapsing the tube upon a short storage piece. These filled storage pieces can be transported, stored and used as the case may require, in a machine or by hand, to be converted into filled bags.

When the stored tubes are to be used, the lower end of the tube is drawn out from under the tension device and pulled down until a proper bag length is released. The lower end is then closed and the material is fed into the funnel above and down through the tube until the bag portion is filled. The tube is then seamed or closed above the bag portion and this part is severed from the rest of the tube to form the finished bag.

By storage piece I mean to include any form of device which will serve to hold the bag tube in its collapsed condition. This storage piece might consist of a single rod or a tube or of two or more rods or any other convenient arrangement for forming a spool with small body and enlarged ends.

I claim—

- 55 1. As a new article of manufacture, a bag forming tube package comprising a storage spool relatively short and small in cross section and having enlargements at its two ends, with a bag forming tube of relatively great length and large cross section collapsed longitudinally and threaded onto said spool between the enlarged ends.
- 60 2. As a new article of manufacture, a bag forming tube package comprising a storage tube relatively short and small in cross

section with a bag forming tube of relatively great length and large cross section threaded and collapsed longitudinally onto said storage tube and means for retaining the bag tube on the storage tube.

70

3. As a new article of manufacture, a bag forming tube package comprising a storage spool with a tubular body open from end to end, and relatively short and small in cross section and having enlargements at its two ends, with a bag forming tube open at both ends and of relatively great length and large cross section collapsed longitudinally and threaded onto said body between the enlarged ends.

80

4. As a new article of manufacture, a bag forming tube package comprising a storage spool with a hollow cylindrical body relatively short and small in cross section and having enlargements at its ends, one of them a funnel, with a bag forming tube of relatively great length and large cross section open at both ends and collapsed longitudinally and threaded onto said body between the enlarged ends.

85

5. As a new article of manufacture, a bag forming tube package comprising a storage spool with a hollow cylindrical body relatively short and small in cross section and having enlargements at its ends, one of them a funnel and the other a tube spreading device, with a bag forming tube of relatively great length and large cross section collapsed longitudinally and threaded onto said body between the enlarged ends.

90

6. As a new article of manufacture, a device for making bags comprising a tubular storage piece having a body relatively short and small in cross section and having an enlargement at the end from which the tube is withdrawn in the bag forming process, the cross-section of said enlargement having an outline materially greater than that of the body, with a bag forming tube of relatively great length and large cross section collapsed longitudinally and threaded onto said body.

105

7. As a new article of manufacture, a storage piece relatively short and small in cross section and having an enlargement at one end, with a bag fabric tube of relatively great length and large cross section open at both ends and collapsed longitudinally and threaded onto said piece.

115

8. As a new article of manufacture, a storage piece having a tubular body relatively short and small in cross section and having an enlargement at one end, the cross-section of the enlargement having an outline materially greater than that of the body, with a bag forming tube of relatively great length and large cross section collapsed longitudinally and threaded onto said body.

125

9. As a new article of manufacture, a

130

storage piece relatively short and small in cross section and having an enlargement at one end, with a bag forming tube of relatively great length and large cross section collapsed longitudinally and threaded onto said piece, and a member associated with such enlargement for yieldingly resisting the withdrawal of the tube therefrom.

10. As a new article of manufacture, a device for making bags comprising a tubular storage piece having a body relatively short and small in cross section and having an enlargement at one end, with a bag forming tube of relatively great length and large cross section collapsed longitudinally and threaded onto said body, and a member associated with such enlargement for yieldingly resisting the withdrawal of the tube therefrom.

15. As a new article of manufacture, a device for making bags comprising a storage spool with a cylindrical body relatively short and small in cross section and having a tubular enlargement at one end and at the other end a funnel, with a bag forming tube of relatively great length and large cross section collapsed longitudinally and threaded onto said body, and a member associated with such enlargement for yieldingly resisting the withdrawal of the tube therefrom.

20. As a new article of manufacture, a storage piece relatively short and small in cross section and having an enlargement at one end, with a bag forming tube of relatively great length and large cross section collapsed longitudinally and threaded onto said piece, and means associated with such enlargement for yieldingly resisting the withdrawal of the tube therefrom, said means comprising an elastic girdle surrounding the storage spool and the fabric tube and adapted to rest upon the enlargement.

25. As a new article of manufacture, a device for making bags comprising a storage piece having a tubular body relatively short and small in cross section and having a tubular enlargement at one end, with a bag forming tube of relatively great length and large cross section collapsed longitudinally and threaded onto said body, and means associated with such enlargement for yieldingly resisting the withdrawal of the tube therefrom, said means comprising an elastic girdle surrounding the storage spool and the fabric tube and adapted to rest upon the enlargement.

30. As a new article of manufacture, a device for making bags comprising a storage piece with a cylindrical body relatively short and small in cross section and having a tubular enlargement at one end and at the other end a funnel, with a bag forming tube of relatively great length and large cross section collapsed longitudinally and threaded onto said body, and means associated with

such enlargement for yieldingly resisting the withdrawal of the tube therefrom, said means comprising an elastic girdle surrounding the storage spool and the fabric tube and adapted to rest upon the enlargement.

35. As a new article of manufacture, a flexible bag forming tube of relatively great length, a short storage piece about which the bag tube is longitudinally collapsed, said piece projecting beyond the tube at each end, and means on the projecting ends of the storage piece for holding the collapsed bag in place upon the storage piece.

40. A bag tube package comprising a short thin storage piece, a long relatively wide flexible bag tube longitudinally collapsed on the storage piece with the storage member projecting beyond each end of the bag tube, and means to retain the bag tube on the storage piece.

45. As a new article of manufacture, a rigid storage tube having an expanded end, a bag tube puckered and threaded onto such storage tube with an end resting against the expanded end, and a yielding girdle surrounding the storage tube and bag tube above the expanded end of the former.

50. As a new article of manufacture, a rigid storage tube having an expanded end, a bag tube puckered and threaded onto such storage tube with an end resting against the expanded end, said expanded end being laterally extended into a narrow and relatively long discharge mouth which tends to spread the bag tube and flatten it as it is withdrawn from the storage tube, and means independent of the storage tube for assisting in normally retaining the bag tube thereon.

55. As a new article of manufacture, a storage piece relatively short and small in cross section and having a bag tube of relatively great length and large cross section open at both ends and collapsed longitudinally onto said storage piece, said storage piece having an enlargement at one end in the form of a spreader substantially larger in cross section than the body of the storage piece and adapted to hold the bag tube on the storage piece and to extend and flatten the bag tube as it is withdrawn therefrom.

60. As a new article of manufacture, a storage piece relatively short and small in cross section, and having an enlargement at one end, with a bag forming tube of relatively great length and large cross section collapsed longitudinally and threaded onto said storage piece, said enlargement being in a form to extend and flatten the bag tube as it is withdrawn therefrom, and a member associated with such enlargement for yieldingly resisting the withdrawal of the bag tube.

65. In testimony whereof, I affix my signature this eighth day of April, 1920.

ADELMER M. BATES.
